UNITED STATES PATENT OFFICE.

MINA C. SPARKS WILLSEY, OF TRENTON, MISSOURI.

SAFETY SEWING-THIMBLE.

1,150,724.

Specification of Letters Patent. Patented Aug. 17, 1915.

Application filed March 11, 1915. Serial No. 13,774.

To all whom it may concern:

Be it known that I, MINA C. SPARKS WILLSEY, a citizen of the United States, residing at Trenton, in the county of Grundy 5 and State of Missouri, have invented a new and useful Safety Sewing-Thimble; and I do hereby declare the following to be a full, clear, and exact description of the invention, such as will enable others skilled in the art 10 to which it appertains to make and use the same.

This invention relates to the art of apparel apparatus, and particularly to an improved thimble adapted more especially for 15 facilitating the forcing of a needle through the fabric while sewing.

Therefore it is the aim to provide the usual conical form of thimble having its closed end concaved, and which concaved 20 end is supplied with a multiplicity of indentures, to prevent the needle, while being forced through an article of apparel, from slipping; and furthermore to provide the outer conical or tapering circumference 25 with a series of annular ribs. The surfaces of these ribs, which face toward the closed end of the thimble are not only concaved, to prevent the needle from slipping off the rib, but are also provided with indentures, 30 to prevent the needle from slipping laterally.

In practical fields the details of construction may necessitate alterations, falling 35 within the scope of what is claimed.

The invention comprises further features and combination of parts, as hereinafter set forth, shown in the drawings and claimed.

In the drawings:—Figure 1 is a view in 40 perspective on an enlarged scale of the thimble constructed in accordance with the invention. Fig. 2 is a vertical sectional view. Fig. 3 is a plan view. Fig. 4 is an

enlarged detail view of a portion of the wall of the thimble. Fig. 5 is an enlarged perspective view of the thimble showing the 45 indentures of the annular rib eliminated.

Referring more particularly to the drawings, 1 designates the conventional form of thimble, preferably conical in shape having its closed end 2 concaved as shown, the 50 outer surface of which concaved end is provided with a series of indentures 3. The outer circumference of the wall of the thimble is provided with a plurality of annular ribs 4, the portions 5 of which are concaved, 55 as shown in sectional view of the drawing to prevent the needle from slipping off the annular rib. The concaved surfaces 5 are supplied with indentures 6 to prevent the needles from slipping annularly. The outer 60 circumference of the thimble between the annular rib is provided with indentures 7.

In Fig. 5 the indentures 6 are dispensed with.

The invention having been set forth, what 65 is claimed as new and useful is:—

A sewing thimble comprising a conical shell body having a closed concaved end, said closed concaved end and the outer circumference of the shell being provided with 70 a multiplicity of indentures, the outer circumference of the shell being formed with a plurality of annular ribs, the surfaces facing toward the closed ends being concaved annularly, the concaved surfaces of 75 the ribs being constructed with indentures to prevent a needle from slipping annularly.

In testimony whereof I have signed my name to this specification in the presence of two subscribing witnesses.

MINA C. SPARKS WILLSEY.
